GARDEN HOSE HOLDER

Filed Dec. 17, 1942

FIG 1

FIG 2

Charles Harvey Churchill
INVENTOR.

B. Prentiss

UNITED STATES PATENT OFFICE

134,939

DESIGN FOR A GARDEN HOSE HOLDER

Charles Harvey Churchill, Cortland, N. Y.

Application December 17, 1942, Serial No. 109,057

Term of patent 3½ years

To all whom it may concern:

Be it known that I, Charles Harvey Churchill, a citizen of the United States, residing at Cortland, in the county of Cortland and State of New York, have invented a new, original, and ornamental Design for a Garden Hose Holder, of which the following is a specification, reference being had to the accompanying drawing, forming part thereof.

I claim:

The ornamental design for a garden hose holder, as shown.

CHARLES HARVEY CHURCHILL.
